VALVE

Tom Wilson, Baltimore, Md., assignor to Bethlehem Steel Company, a corporation of Pennsylvania

Application November 4, 1938, Serial No. 238,819

6 Claims. (Cl. 137—53)

The object of my invention is to provide a device to be used in combination with a gas supply line leading from apparatus which produces gas intermittently, in order to prevent backfeeding of the gas to such apparatus when the pressure therein falls below that in the remainder of the line.

I have found my invention to be of value in connection with the utilization of gas produced in blast furnaces. During the operation of a blast furnace, great quantities of gas are produced, which gas may conveniently be used for the operation of coke ovens, gas engines and the like. It is customary to provide in the line leading from the blast furnace to the coke ovens or the like an expansible and collapsible gasometer or other holder capable of storing the excess gas produced, and of feeding such excess gas to the coke ovens when the gas supply from the blast furnace fails. Although a blast furnace produces large quantities of gas, the production is intermittent, and fails when the blast furnace is being charged or tapped. Such failure reduces the pressure of the gas in the line leading from the blast furnace below that in the gas holder, with the result that backfeeding of the gas from the gasometer to the blast furnace takes place. This of course greatly reduces the ability of the gasometer to provide an uninterrupted flow of gas to the coke ovens.

My invention comprises novel means of preventing such backfeeding of gas through the use of a liquid sealed valve of special construction automatically operated by differentials in the pressure of the gas on either side of the valve. Thus, the valve is so arranged that when the gas pressure on the blast furnace side exceeds by a predetermined amount the gas pressure on the gasometer side, the valve will automatically open to allow gas to flow from the blast furnace into the gasometer and coke oven mains. Upon a reversal of these conditions the valve automatically closes and prevents the backfeeding of gas from the gasometer to the blast furnace.

It is obvious that if gas is produced by the blast furnace in excess of its consumption, the gasometer will eventually become filled. Therefore, means may be provided in my invention to automatically close said valve when the gasometer becomes full, regardless of the fact that the gas pressure on the blast furnace side of the valve exceeds that on the gasometer side.

The valve, although useful in connection with the production of gas by a blast furnace, is not limited to such use but will operate successfully in any gas line in which it is desired to maintain a flow of gas in only one direction.

The exact nature of my invention is more fully set forth in the following specification, as well as in the drawings in which

- Fig. 1 is a sectional view of the valve;
 10 Fig. 2 is a plan view of the valve taken along the line 2—2 of Fig. 1;
 Fig. 3 is a sectional view of the water cups used to seal the valve raising and lowering mechanism;
 15 Fig. 4 is a view in elevation of the arrangement of counterweights employed to actuate the valve; and
 Figs. 5 to 9 are sectional views of the valve showing the positions which it assumes under various operating conditions.
- Figure 1 shows in detail the construction of the water seal valve 22. Said valve, which is preferably constructed of sheet metal, comprises a cylindrical wall 37, top 38 and bottom 39, which may be assembled in any convenient manner as by angle irons 40 and 41 to form a closed cylinder. Located slightly above the point at which the pipe 21 enters the water seal valve 22, is an annular plate 42, the outer edge of which may be secured to the wall 37 by means of the angle iron 43. Braces 44 may be employed to reinforce the plate 42. At the inner edge of plate 42 is fastened the open ended pipe or cylinder 45 through which the gas entering the valve at 21 is enabled to flow.
- It will be seen that cylinders 37 and 45, together with the plate 42, form an annular trough 46 adapted to hold water or other liquid 47 and to act as a liquid seal trough for the gases entering the valve. 48 is a gauge for determining the level of the liquid in the tank, which level may be regulated by the overflow valve 49.
- 40 Superimposed upon the cylinder 45, and dipping into the trough 46, is the inverted cylindrical bell 50 comprising skirt 51 and top 52. Guides 53 may be spaced around the perimeter of the bell at suitable intervals to center the bell upon the cylinder 45. Fastened to the top 52 of the bell is the rope or other lifting means 54 to which is fastened a counterweight at a convenient point outside the cylinder 37. Also fastened to the top 52 of the bell is the stop 55 which limits the upward movement of the bell.

In order to prevent the escape of gas at the point where the rope 54 passes through the top 38 there is provided the water cup 56 through which the rope 54 passes. The water cup 56 will be more fully described hereinafter. At the bottom of the water cup 56 is the stop 57 which limits the upward movement of the bell 50. The upper end of the cylinder 45 is provided with one or more slots 125 which permits the flow of gas into the space 126 between the wall of the cylinder 45 and the skirt 51 of bell 50.

Superimposed upon the bell 50 and dipping into the trough 46 is the inverted cylindrical open bell 58 which comprises the skirt 59 and the inwardly extending annular flange 60, which is of such width that its inner edge 61 rests upon the top 52 of the bell 50. The inner edge of the flange 60 may be reinforced by the angle iron 62. At their point of contact, the surfaces of the top 52 and the flange 60 are finished so as to provide a gas tight joint, but the bells 50 and 58 are not fastened together and are free to move independently of each other. The skirt 59 of bell 58 is longer than the skirt 51 of bell 50, but the exact difference in length of said skirts is immaterial.

The bell 58 is suspended by the ropes 54' which in the embodiment here shown are three in number, although only two are visible in Figure 1. These ropes pass through the water cups 56' which are identical with the water cup 56 and are provided with stops 57'. Stops 55' are suitably fastened to the flange 60 and are similar to stop 55, but shorter, so that bell 58 has a greater range of vertical movement than bell 50.

At convenient points on the periphery of the skirt 59 may be provided the outwardly extending wings 63 which run in guides 64 fastened to the interior of the wall 37 and prevent the rotation of the bell 58 as it rises and falls. Likewise, inwardly extending wings 65 may be fastened to the skirt 59 to keep the bell 58 centered upon the cylinder 45.

Referring to Figure 2, it will be seen that the rope 54 extends vertically above the top of the water seal valve 38 and the water cup 56. The ropes 54' by which the outer bell 58 is suspended converge at a point above the top of the water seal valve 38. In order to keep the ropes 54' from pulling inwardly against the water cups 56', the rods 66 are provided, which effectively hold the ropes 54' in alignment with the said water cups.

Figure 3 shows the construction of the water cups 56 and 56'. The water cups consist of two concentric cylinders 67 and 68 fastened together at their bottom by an annular plate 69 and constituting a deep annular trough 70 which may be filled with water or other liquid 71. The rope 54 extends upwardly through the inner cylinder 67 and may be secured at its upper end to the eye-bolt 72. Suitably secured to the eye-bolt 72 is the conical element 73 from which the cylinder 74 depends and extends into the annular trough 70. The connections between the eye-bolt 72 on the one hand and the rope 54 and the depending cylinder 74 are made gas tight.

It will be apparent that the water cup 56 hereinabove described provides a water seal which operates on well known principles to prevent the escape of gas from the gas control valve as the bells 50 and 58 are raised and lowered.

The stops 57 and 57' hereinabove referred to are shown to consist of an extension 75 of the

cylinder 67, to the lower end of which extension is fastened the annular flange 76.

Figure 4 shows the manner in which the bells 50 and 58 are counterweighted. The rope 54 which carries the bell 50 passes over the sheaves 77 and 78 and is provided with the counterweight 79; while the ropes 54' are brought to a common point by the link 80 and are thereafter extended as a single rope 81 which passes through the fixed sheaves 82, 83 and 84 and the adjustable sheave 85 and is provided with the counterweight 86.

Located in the inlet pipe 21 immediately in front of the water seal valve 22 is the butterfly valve 31 hereinabove referred to. Butterfly valve 31 is of well known construction comprising a disk 87 (shown in Figure 4 in a horizontal or open position) suitably pivoted in the walls of pipe 21 at 88 and 89, and having the arm 90 extending beyond the outer surface of pipe 21. To arm 90 is fastened the lever 91 which carries counterweight 92 as well as rope 93. Rope 93 is carried over sheaves 94, 95, 96 and 97 as well as adjustable sheave 98 and is secured to counterweight 99. Counterweights 92 and 99 are so adjusted that the valve disk 87 is normally in its horizontal or open position, but may be closed by raising counterweight 93 in the manner hereinafter to be described.

It will be seen from Figure 4 that the gasometer 25 comprises an outer shell 100 suitably secured to the bottom 101 and provided with the bearing members 102 upon which lifts 103, 104 and 105 rest. The interior of the gasometer is filled with water 106 which forms a water seal of well known type.

At or near the top of the shell 100 are provided the sheaves 108 and 109 which carry the rope 110. This rope 110 is fastened at its lower end to counterweight 99 hereinabove referred to.

In order to guide counterweight 99 in its travel, it is provided with wheels 111 which are adapted to run upon track 112 fastened to the shell 100 at 113 and 114. It is also provided with the hole 115 through which the rope 81, previously referred to, runs.

The opposite end of rope 110 is carried up and over sheave 116 and is provided with counterweight 117.

At or near the top of the lift 103 is the bracket 118 provided with the hole 119 through which rope 110 runs.

It is now possible to describe the mode of operation of the water seal valve 22. As heretofore explained, the bells 50 and 58 are provided, respectively, with the counterweights 79 and 86. The exact weights of the bells and counterweights may be varied to suit the operating conditions encountered in practice, but in order to explain the principles upon which the valve operates an actual embodiment of the invention will be described. In this embodiment the weights of said bells and counterweights are as follows:

	Pounds
A. (Bell 50)	1022
B. (Bell 58)	2845
C. (Counterweight 79)	1112
D. (Counterweight 86)	2553

It will be seen that the combined weights of A and B (3867 lbs.) exceed the combined weights of C and D (3665 lbs.) by 202 lbs. Accordingly, when the pressure of gas flowing from gasometer 25 through pipes 24 and 23 into the upper part of the valve body equals or exceeds that flowing through the pipe 21 into cylinder 45, the bells 50

and 58 will assume the position shown in Figure 5 and the flow of gas in either direction through the valve will be prevented by means of the water seal.

If the gas pressure in cylinder 45 is now increased so that the differential in pressure above and below the bells exceeds 202 lbs., bells 50 and 58 will rise until the stop 55 contacts the stop 57, as shown in Figure 6. In this position the skirt 51 of bell 50 is completely out of the water, while the skirt 59 of bell 58 remains in the water seal. Moreover, since the weight B (2845 lbs.) exceeds the weight D (2553 lbs.) by 292 lbs., it is evident that the bell 58 will continue to rest upon the bell 50 with the result that the flow of gas through the valve is still prevented.

If now the pressure of the gas in the inlet line 21 and cylinder 45 is increased until the differential in pressure exceeds the 292 lbs. which hold bell 58 against bell 50, bell 58 is enabled to rise until stop 55' contacts stop 57' as shown in Figure 7. In this position of the bells gas will flow through the valve 22 in the manner indicated by the arrow 119 whence it will flow either to the gasometer 25 or through the pipe 27 to the coke ovens or the like.

The foregoing illustration is given by way of example only. Obviously the actual weights of the bells and their counterweights may be varied to suit the gas pressures to be encountered in actual practice and the results desired. Obviously, also, with bells and counterweights of any specified weights, the bells will be made of such size that they will operate under the pressures desired. For example, if a valve in which the bells and counterweights have the weights above specified is installed in a main leading from a blast furnace to a gasometer, where comparatively low gas pressures are encountered the diameter of the inner bell may conveniently be made four feet and the diameter of the outer bell six feet six inches. With such dimensions, a pressure differential of approximately .11 pound per square inch, or approximately 3.1 inches of water, will be required to raise the inner and outer bells to the position shown in Fig. 6. To raise the outer bell to the position shown in Fig. 7, and thus open the valve, an additional pressure differential of approximately .098 pound per square inch or approximately 2.75 inches of water will be required. Obviously, the skirts of both bells will be made of such depth that the water seals will not blow under the above conditions or under any other conditions of pressure which may occasionally exist in the line. Obviously, also, changes in the respective areas of the bells will affect the pressures required to operate them under the weight conditions assumed. These matters will be readily understood by one skilled in the art.

It will be noted that through the use of the two bells 50 and 58 the gas when flowing through the valve 22 does not pass through the water which constitutes the sealing medium. This is an important result which is obtained through the use of my invention, since it is well known that the passage of gas through the water, which would occur if bell 50 were used alone without bell 58, has a deleterious effect upon the gas, and also increases the difficulty of maintaining the water seal at its proper level.

From the description hereinabove given of the valve, it will be apparent that if for any reason the pressure of the gas in the inlet line 21 falls below the 292 lbs. required to raise bell 58 from

its seat on bell 50, bell 58 will immediately fall and thereby reestablish a seal which will prevent the back flow of gas from the gasometer 25 to the inlet line 21. This is the primary function accomplished by the valve 22. It is obvious that the backfeeding of gas from the gasometer 25 to the inlet line 21 is wasteful of gas and creates a hazard of fire or explosion. This is completely prevented by the valve hereinabove described. Moreover, the use of such a valve by preventing the backfeeding of gas from the gasometer insures the presence of sufficient gas in the gasometer to run the coke ovens for a period of time, with the result that it is not necessary to place the coke ovens on neutral position immediately upon the cessation of flow of gas from the source of supply.

As heretofore shown, the several functions performed by the valve 22 are accomplished through the assembly of the bells 50 and 58 and the counterweights 78 and 86 in the manner immediately hereinabove set forth. In order, however, to perform these functions more successfully, the said valve may, if desired, be equipped with the auxiliary devices now to be described.

Reference to Figure 4 shows that lift 103 is furnished with a bracket 118 through which rope 110 runs. At a point somewhat below the position assumed by bracket 118 when the gasometer 25 is filled with gas and lift 103 is in its highest position, rope 110 is provided with a stop 120. When, because of gas flowing into the gasometer 25 through valve 22, lift 103 rises, bracket 118 will assume the position 118' and engage stop 120. As lift 103 rises still further bracket 118 will assume the position shown at 118'' and will raise stop 120 to the position shown at 120'. The raising of stop 120 will raise counterweight 99, which, by engaging stop 121 secured to rope 81, will raise counterweight 86.

The release of bell 58 from the effect of counterweight 86 will immediately cause said bell to fall and reestablish a seal which will prevent the further flow of gas through valve 22 and into the gasometer, as shown in Figure 8. Under this condition the combined weights A and B (3867 lbs.) will exceed weight C (1112 lbs.) by 2755 lbs., with the result that even a great increase in the pressure of the incoming gas will not break the seal so established.

It will be seen therefore that valve 22 which prevents backfeeding of gas from the gasometer to the inlet line may, through the use of auxiliary means for raising counterweight 86, be adapted to prevent the flow of gas into the gasometer 25 when the latter is full.

Figure 9 shows the valve 22 when the lift 103 is in its high position and the pressure in the inlet line falls below that in the holder. In this position the bells 50 and 58 will be in their low position and will, as before described, effectively prevent the backfeeding of gas from the gasometer to the inlet line. In Figure 9 it will be seen that the pressure of gas from the gasometer has raised the water level in the space between cylinder 45 and inner bell 50.

When the lift 103 drops and releases counterweight 86, bells 50 and 58 will still remain closed until the pressure in the gasometer drops sufficiently below that in the inlet line to enable the bells to rise and break the seal.

Referring again to Figure 4, it will be seen that when lift 103 reaches its high position and raises counterweight 99, lever 91 attached to butterfly valve 31 will immediately fall and close inlet line

21. As is the case with the auxiliary means for engaging counterweight 86, butterfly valve 31 is not essential for the operation of valve 22 but simply provides additional means for shutting off the supply of gas when the gasometer 25 is filled.

It will be seen from the foregoing description that the present invention comprises a water seal valve which permits the flow of gas from the source of supply to a gasometer and to the place of consumption of the gas, but automatically prevents the backfeeding of gas when the supply fails. The valve, moreover, is so constructed that gas flowing through the valve does not pass through the water which constitutes the seal. Auxiliary to the water seal valve is means actuated by the gasometer to close the valve when the gasometer is full; but this is not essential to the operation of the valve. There is also provided a butterfly valve which closes automatically when the gasometer is full. This valve is also auxiliary to the water seal valve and is not essential for its successful operation.

Although I have described specific means for operating the water seal valve and the auxiliary apparatus, it is obvious that other means might be provided for performing these functions. In particular, I have given specific weights for the bells 50 and 58 and their respective counterweights. These weights, however, are merely illustrative of a successful embodiment of my invention. It is obvious that if the bells are constructed of lighter materials, or if it is desired to increase the pressures required to open the valve, the counterweights might be entirely dispensed with. In such case, it would be possible, without departing from the spirit of my invention, to provide auxiliary means operated by the gasometer for the purpose of lowering the open bell 58 when the gasometer is full. The only rule which must be observed in constructing the bells 50 and 58 is to so proportion the weights of the bells that the outer bell will not rise from its seat on the inner bell until the latter is completely out of the water seal.

It is also obvious that although I have described the water seal valve 22 in conjunction with a gasometer, the gasometer is not essential to the operation of the valve, since the valve is equally effective to prevent backfeeding of gas when used in a pipe line leading directly from the source of supply to the point of consumption.

Having thus described my invention, what I claim as new and desire to secure by Letters Patent is:

1. A valve for a gas main comprising an inlet pipe adapted to lead from the said main, a water sealed bell covering said inlet pipe and adapted to move upwardly in response to increasing pressure of gas in the inlet pipe and to move downwardly in response to decreasing pressure of gas in the inlet pipe, a second water sealed bell seated on said first mentioned bell and movable therewith, said second mentioned bell being adapted to move upwardly independently of said first mentioned bell in response to a further increase of gas pressure in the inlet pipe thereby breaking said seat and permitting the flow of gas therethrough.

2. A valve for a gas main comprising an inlet pipe adapted to lead from the said main, a water sealed bell covering said inlet pipe, a second water

sealed bell seated upon said first mentioned bell, said bells being movable upwardly in seated relationship in response to an increase of gas pressure in the inlet line to break the water seal of the first mentioned bell, said second mentioned bell being further movable upwardly in response to a further increase of gas pressure in the inlet line to unseat said second bell and permit the flow of gas therethrough.

3. A valve for a gas main, comprising an outer shell, an inlet pipe adapted to lead from said main into the interior of said shell, a water sealed bell covering one end of said inlet pipe and adapted to move upwardly to break the water seal in response to an increase in the gas pressure in the inlet pipe, a second water sealed bell seated on said first bell and movable therewith, second bell having a longer skirt than said first bell, said second bell being adapted to move upwardly independently of said first bell in response to a further increase in the gas pressure in the inlet pipe thereby breaking said seat and permitting the flow of gas therethrough, and means for limiting the upward movement of said second bell to prevent the breaking of the water seal of said second bell.

4. A valve for a gas main, comprising an inlet pipe adapted to lead from said main, a water sealed bell covering one end of said inlet pipe, a second water sealed bell seated upon said first bell, an opening in the top of said second bell, said bells being movable upwardly in seated relationship in response to an increase of gas pressure in the inlet pipe to break the water seal of said first bell, said second bell being further movable upwardly in response to a further increase of gas pressure in the inlet pipe to unseat said second bell and permit the flow of gas through the opening in the top thereof.

5. A valve for a gas main comprising an inlet pipe adapted to lead from said main, a water sealed bell covering one end of said inlet pipe, a second water sealed bell seated on said first bell, said bells being normally adapted to move upwardly in response to an increase in the gas pressure in the inlet pipe, and said second bell being normally adapted to move further upwardly in response to a further increase in the gas pressure in the inlet pipe to unseat said second bell and permit the flow of gas therethrough, a counterweight for said second bell, and means for rendering said counterweight ineffective, whereby the upward movement of said bells in response to a further increase in the gas pressure in the inlet pipe is prevented.

6. A valve for a gas main comprising a shell, and inlet pipe adapted to lead from the gas main to the interior of said shell, a water sealed bell covering one end of said inlet pipe and adapted to move upwardly in response to an increase in the gas pressure in the inlet pipe to break said seal, a second water sealed bell seated on said first bell and movable therewith, said second bell being adapted to move further upwardly in response to a further increase in the gas pressure in the inlet pipe to break said seat and permit the flow of gas therethrough, a counterweight for said second bell, and means for rendering said counterweight ineffective whereby such further upward movement of said second bell is prevented.
